UNITED STATES PATENT OFFICE

2,689,060

COVER OR LID FOR BOXES

Abe Katzman, Bronx, N. Y., assignor to I. D. Company, New York, N. Y., a firm

Application March 13, 1951, Serial No. 215,267

2 Claims. (Cl. 220—42)

1

This invention relates to improvements in covers or lids for boxes and it relates more particularly to boxes having covers or lids which simulate, and may be used as, framed pictures suitable to be hung on the wall.

It is common practice to print or lithograph decorative material, pictures and the like on the covers of boxes used for packaging candies, cookies and other articles. While many of these box covers or lids are highly ornamental and decorative, they have not been used for wall decorations for the reason that they resemble nothing other than a box lid or cover. This unmistakable box cover effect is produced by the flange around the edge of the lid and in the case of metal lids, the rolled bead around the outer edge of the flange. Efforts to print or lithograph a frame pattern around the edge of the cover are not successful because the resulting structure still resembles a decorative box lid.

It is, of course, old to provide vanity and jewel boxes with wood framed tops which might be used as pictures, but in these more expensive boxes the lids or covers are hinged to the body of the box and are not detachable.

The present invention involves a modification of the structure of the lid of a disposable box to provide a top which is a faithful representation of a framed picture with none of the characteristics of a box lid, after the lid is detached from the box. More particularly, a sheet metal lid is formed with a raised and suitably shaped frame enclosing a depressed area to receive the picture. The flange which receives the top of the box body forms the outer edge of the frame and the rolled bead at the edge of the frame is rolled inside the flange to render it invisible when the lid is hung on a wall.

The raised frame edge on the lid would normally permit the recessed portion of the lid to project into the top of the box body, thereby reducing its capacity. This disadvantage has been overcome by shaping the frame so that the lid can slide down only a predetermined distance over the box body or by inserting a sheet within the lid which limits the distance that the box body can enter the lid.

The lid structure described generally above can be provided with a wide variety of ornamental subjects. The raised frame edge can be lithographed or covered with wood grain decals to resemble a wooden frame or a frame of any other desired material. The picture or decorative material can be lithographed or printed in the recessed area, or the decorative material can be

2

separately prepared and cemented in the recessed area. Moreover, the recessed area may be embossed in intaglio or relief and given an appearance of substantial thickness or depth.

5 The inwardly rolled flange forms a convenient means for hanging the lid on the wall. It can readily engage a nail or picture frame hook so that it is unnecessary to provide the lid with means for attaching a picture frame wire or the like to the lid.

For a better understanding of the present invention, reference may be had to the accompanying drawings in which:

Fig. 1 is a view in perspective of a box having 15 a cover of the type embodying the present invention, and

Fig. 2 is a view in section taken on line 2—2 of Fig. 1.

The box and box lid or cover disclosed in 20 Figs. 1 and 2 of the drawings is typical of the various types of box and lid constructions that may be provided in accordance with the present invention. As shown in Figs. 1 and 2, the box includes a box body portion 10 of generally rectangular shape having a bottom 11 and side walls 12, 13, 14 and 15 of substantially any desired height depending upon the intended capacity of the box. While the box is illustrated as rectangular, it will be understood that it can be 25 square, circular or of any other polygonal or desired shape.

The cover 16 of the box preferably is formed 30 of sheet metal for durability and ease of manufacture and is characterized by a central depressed or recessed portion 17 of rectangular or other desired shape, and a raised rim or edge portion 18 terminating in a depending flange 19 adapted to receive telescopically the upper edges of the side walls 12 to 15 as best shown in 35 Fig. 2. The cover or lid 16 may be produced by a simple stamping operation so as to impart the desired configuration and cross-sectional shape 40 of the lid.

The central depressed portion 17 of the lid is 45 adapted to receive ornamental material such as a picture P or the like of a type suitable to be hung upon a wall. The picture material P may be printed or lithographed directly on the surface of the top or it may be applied in the form 50 of a decal or formed separately on paper, fabric or the like, and cemented or otherwise secured in the depressed area 17.

The rim portion 18 in cross section corresponds 55 to the cross section of a picture frame. As illustrated, the rim portion 18 is bounded on its

outer edge by the flange 19 which is generally perpendicular to the plane of the recessed portion 17 and is joined at its upper edge by an inclined plane portion 20 to a shoulder or step 21 which further imparts depth and solidity to the rim portion. It will be understood, of course, that the cross-sectional shape of the rim portion 18 may be modified to simulate any desired type of picture frame molding of plain or ornamental type.

In order to avoid the lid-like appearance which characterizes ordinary metal covers or lids for boxes, the bead 22 at the lower edge of the flange 19 is rolled inwardly so as to make the bead inconspicuous and actually invisible when the lid is hung upon the wall. The inwardly rolled bead 22 also serves as a convenient means for engaging a picture frame hook or nail to facilitate hanging the lid on the wall.

The raised rim portion 18 of the box would normally allow the side walls 12 to 15 of the box body 10 to telescope into the lid 16 to such an extent that the capacity of the box would be markedly reduced. This disadvantage of the recessed rim can be overcome in the following way. For example, as shown in Fig. 2, a sheet of metal 23 or other similar stiff material can be inserted within the lid 16 so that it spans the area within the flange 19 and bears against the underside of the recessed portion 17. The sheet 23 prevents the box body from entering the lid much farther than the plane of the bottom of the recess 17.

The sheet of metal or other material 23 may be conveniently secured in the lid by providing it with a depending flange or flanges 24 which bear against the inner surface of the lid flange 19 and have their lower edges inserted between the edge of the rolled bead 22 and the flange 19. This affords a stiff, sturdy structure which prevents collapse of the sheet under pressure and thereby assures uniform capacity for the box when the lid is applied to it.

Box lids embodying the present invention are susceptible to considerable modification and may be simplified and otherwise changed as the purpose demands.

It will be understood that the picture material P applied to the center depressed portion of the lid may be of any desired type and preferably is of such nature as to render it most desirable for use as a wall hanging. Also, the rim or frame

portion of the box may be suitably lithographed or decorated with decals to give a wood grain or other ornamental appearance simulating known types of picture frames, depending upon the pictorial material P formed in the box lid. Therefore, the forms of the invention disclosed herein should be considered as illustrative and not as limiting the scope of the following claims.

10 I claim:

1. A container comprising a hollow box body having a bottom and upstanding side walls having upper edges defining an open top, a lid for closing said open top of said body, said lid having a depressed center portion to receive ornamental material and a raised periphery terminating in a peripheral flange to receive said side walls telescopically, said raised periphery and flange simulating a picture frame, said flange having a bead at its outer edge rolled inside said flange for engagement with the side walls of said body and a sheet of material inside and spanning the space within the flange on said lid and substantially engaging the inner side of said depressed portion, said sheet being engageable with the upper edges of said side walls to limit the telescoping of said edges to about the plane of said depressed center portion.

2. The container set forth in claim 1 wherein said sheet of material has side flanges extending parallel with the flange on said lid and engaged between said bead and the last-mentioned flange.
